UNITED STATES PATENT OFFICE.

STEPHEN D. BAKER, OF NEW YORK, N. Y.

DESIGN FOR A BRACKET FOR BATHROOM FIXTURES.

Application filed December 31, 1921. Serial No. 526,396. Term of patent 14 years.

To all whom it may concern:

Be it known that I, STEPHEN D. BAKER, a citizen of the United States, and a resident of New York city, in the county of New York and State of New York, have invented a new, original, and ornamental Design for a Bracket for Bathroom Fixtures, of which the following is a specification, reference being had to the accompanying drawings, forming part thereof.

In the drawings:

The single figure is a perspective view of a bracket for a bath-room fixture embodying my design, the rail or bar being broken away to indicate variability of length.

I claim:

The ornamental design for a bracket for bathroom fixtures, as shown.

STEPHEN D. BAKER.
